WELL PACKER AND ANCHORING MEANS
THEREFORRobert K. Le Rouax, Houston, Tex., assignor to
Oil Center Tool Company, Houston, Tex., a cor-
poration of Texas

Application September 2, 1950, Serial No. 183,027

8 Claims. (Cl. 166—12)

1

This invention relates to new and useful improvements in well packers and anchoring means therefor.

One object of the invention is to provide an improved well packer which is adapted to be set or anchored within a well solely by a longitudinal movement of the supporting pipe string or mandrel, whereby the requirement that the support for the packer be rotated in order to set the packer is obviated and the disadvantages of rotation are eliminated.

An important object of the invention is to provide an improved well packer having a latching assembly associated with the anchoring means for normally latching the anchoring means against operation to permit lowering of the packer to the desired position within a well bore; said latching assembly being operable by hydraulic pressure to release the packer anchoring means for actuation.

Another object is to provide an improved well packer having the usual anchoring slip assembly, together with a latch means for normally latching the slip assembly in position against relative upward movement on the packer support; the device also including a release means operable by fluid pressure from above and adapted to coat with the latch means for disengaging the same to permit subsequent setting of the slip assembly by lowering of the packer support relative to said assembly.

A further object of the invention is to provide an improved anchoring means for a well packer including anchoring slips and a latch means for normally latching the slips in position which prevents their moving to a set position, with the arrangement being such that in the event the latching means is prematurely released, it may be reset without removing the entire well packer from the well bore.

Still another object of the invention is to provide an improved anchoring means for a well packer which is adapted to be moved into a set or packer-supporting position by a downward movement of the supporting mandrel of the packer and which is adapted to be released by a longitudinal upward movement of the supporting mandrel, whereby rotation of the supporting mandrel to effect either setting or release is unnecessary.

Still another object is to provide an improved well packer which is simple in construction and comprises a minimum number of parts and which has means for permitting a washing operation to be carried out just prior to the final setting of the packer.

2

Still another object is to provide an anchoring assembly which includes anchoring slips, together with a novel means for limiting the outward movement or radial expansion of the slips by its expanding member or cone.

The construction designed to carry out the invention will be hereinafter described together with other features thereof.

The invention will be more readily understood from a reading of the following specification and by reference to the accompanying drawings forming a part thereof, wherein an example of the invention is shown, and wherein:

Figure 1 is a view of a well packer constructed in accordance with the invention and showing the same in position being lowered through a well pipe with the anchoring means being latched against operation.

Figure 2 is a similar view illustrating the latching mechanism released in preparation for setting of the slips.

Figure 3 is a similar view illustrating the packer in its fully set position.

Figure 4 is an enlarged longitudinal sectional view of the upper portion of the packer showing the parts in the position during lowering of the packer.

Figure 5 is a continuation of Figure 4 of the intermediate portion of the packer.

Figure 6 is a continuation of Figure 5 showing the lower portion of the packer and illustrating the latching means in its latched position.

Figure 7 is a horizontal cross-sectional view taken on the line 7—7 of Figure 6.

Figure 8 is a horizontal cross-sectional view taken on the line 8—8 of Figure 6.

Figure 9 is an enlarged longitudinal sectional view of the upper portion of the packer showing the same in its set position.

Figure 10 is a continuation of Figure 9 illustrating the lower portion of the packer when in its set position, and

Figure 11 is a horizontal cross-sectional view taken on the line 11—11 of Figure 9.

In the drawings, the numeral 10 designates a well pipe or casing which is disposed within a well bore A and within which the improved well packer is adapted to be set or anchored. The packer is adapted to be lowered on an inner pipe or tubing string 11 and the tubing forms the sole support for the packer, whereby the same may be lowered and raised within the well casing.

As is clearly shown in Figure 1, the well packer includes a packer assembly B at its upper end, an anchoring mechanism C at its intermediate

portion and a latching assembly D at its lower portion. The latching assembly D, as will be hereinafter explained, is arranged to normally lock the anchoring mechanism C against actuation whereby the packer may be lowered into the well casing A to the desired position therein. When the latching assembly is operated, the anchoring mechanism C is released for actuation and by a longitudinal movement of the packer support or tubing 11 said anchoring mechanism may be set, after which the packer assembly may be expanded to pack off between the inner supporting string or tubing 11 and the well casing A. The arrangement is such that when it is desired to remove the packer, it is only necessary to pull upwardly on the inner supporting string or tubing 11 and this will result, as will be explained, in the packer assembly B and the anchoring mechanism C being released so that the entire unit may be removed from the well casing. It is pointed out that the structure is such that rotation of the inner string or tubing 11 which supports the well packer is unnecessary to either set the anchoring mechanism or release the same.

Referring to Figures 3 to 5 the inner supporting string or tubing 11 has a valve head 12 connected therein and said head is formed with a seating surface 13 which may have an annular packing ring 14 mounted therein. A section 11a of the tubing extends downwardly from the valve head 12 and projects entirely through the well packer. At its lower end the section 11a has a coupling collar 15 threaded thereon and a tail pipe 16 extends downwardly from the collar. The upper surface of the collar (Figure 6) is curved as indicated at 15a and this curved surface merges into the lower end of longitudinal recesses 17 which are formed in the external surface of the lower portion of the tubing section 11a. These recesses, together with the curved upper surface of the collar 15a, provide by-passes, as will be hereinafter explained.

The packer assembly B includes a tubular mandrel 18 (Figure 4) which surrounds the upper portion of the tubing section 11a and the upper end of the mandrel has an annular valve seat member 19 secured thereto. The member 19 is formed with an inclined seat 20 which is adapted to be engaged by the seating surface 13 of the valve head. The bore of the mandrel 18 is of larger diameter than the external diameter of the tubing section 11a whereby a flow passage 21 is provided between the mandrel and the tubing section. A pair of superposed packing sleeves 22 surround the mandrel and have flanged retaining collars 23 confining the upper and lower ends of said packing sleeves. The lower retaining collar of the lowermost packing sleeve engages the upper end of a tubular perforated section 24 which section encircles the tubing 11a in spaced relationship thereto. The perforated section 24 having a plurality of radial perforations 25 is connected to the lower end of the mandrel 18 by a shear pin 26, and thus the packing elements 22 are confined on the mandrel 18 between the upper valve seat member 19 which is secured to the upper end of the mandrel, as by welding 19a, and the perforated tubular section 24. The external surface of the packing elements 22 is normally of a diameter less than the bore of the well casing 10, and thus, so long as the shear pin 26 connects the mandrel to the perforated section 24, distortion of the packing elements cannot be effected.

The tubular perforated section 24 which encircles the supporting tubing 11a has its lower end welded or otherwise secured to an expander cone 27 which surrounds the section 11a (Figure 5) and said cone is normally attached to the section 11a by a shear pin 28. It is noted that the shear pin 28 is of lesser strength than the shear pin 26 whereby the pin 28 will shear under a lesser weight than will the upper shear pin. The expander cone 27 has its lower end engaging an external shoulder 29 which is formed on the tubular supporting section 11a.

The slip expander cone 27 is adapted to coact with gripping slips 30 and these slips have been illustrated as three in number although, of course, any desired number may be employed. Each slip is arcuate in cross-section and has gripping teeth 31 formed on its external surface. The lower portion of the inner surface 32 of each slip generally conforms to the external surface of the supporting tubing section 11a while the upper portion of the inner surface of each slip is inclined or tapered as indicated at 33; the tapered portion 33 of the inner portion of each slip is adapted to coact with the inclined outer surface of the expander cone 27 when the expander cone is moved downwardly between the slips as illustrated in Figure 9. For limiting the extent of expansion of the slips by the cone the lower portion of each slip is formed with an internal groove 34 which receives a stop ring 35 (Figure 5). The bore or opening through the stop ring 35 is of a diameter which is larger than the exterior of the section 11a but is less than the external diameter of the lower end 27a of the expander cone. Thus, when the expander cone is moved downwardly within the slips 30 as shown in Figure 9 the slips are moved outwardly into engagement with the bore of the well casing A and the movement of the cone within the slips is limited by the engagement of the lower end 27a of said cone with the stop ring 35.

Each gripping slip 30 is connected by a flexible strap 36 with a collar 37 which surrounds the section 11a. The collar 37 forms the upper end of a friction spring assembly which assembly includes a tubular body 38 having spring-pressed friction shoes 39 mounted thereon and normally expanded by coil springs 40. The friction shoes 39 engage the wall of the well casing and are maintained in frictional contact therewith by the springs 40.

Secured to the lower end of the tubular body 38 of the friction spring assembly are a plurality of elongate latch arms 41 and each arm extends longitudinally of the tubing section 11a. Each arm is constructed of flat spring material which constantly urges the lower end of the arm inwardly into contact with the external surface of the tubing section 11a. The lower portion of each arm is formed with an inwardly projecting latching dog 42, which dog has its upper surface inclined inwardly at 43. The lower portion of the dog is beveled or tapered inwardly at 44, and this inclined surface terminates just above the lower end of the latch arm. Above the dog 42, the inner surface of each latch arm is provided with a groove 45 and above the groove a relatively elongate projection 46 is formed. The upper surface 47 of the projection 46 is generally tapered or inclined as is shown in Figure 6.

Each latch arm 41 is arranged to coact with an annular groove or recess 48 which is formed in the external surface of the tubing section 11a.

The upper wall 49 of the groove or recess is inclined complementary to the inclined upper surface 43 of each latching dog while the lower portion of said groove is tapered as indicated at 50 in Figure 6. The latching dogs 42 of the latch arms 41 are adapted to be engaged within the groove or recess 48 in the external surface of the tubing section 11a and are maintained in such engagement by the inherent resiliency or flexibility of the spring latch arms 41. When so engaged it will be evident that a lowering of the tubing 11 and the tubing section 11a will result in the latching dogs 42 remaining in engagement with the groove 48. This engagement is effected by the contact of the shoulder 49 of the groove 48 with the upper surface of the latching dogs 42. Since the latch arms 41 are directly connected to the friction spring assembly of the anchoring unit C, it will be evident that with the latch arms connected to the section 11a, the section 11a and the anchoring unit C will move downwardly as a unit; the packer assembly element is connected through shear pin 28, cone 27, perforated section 24 and shear pin 26 to section 11a so that the assembly B also moves downwardly with the tubing and anchoring unit. It is, therefore, evident that with the latching dogs 42 engaging the annular groove 48 in the tubular section 11a the various parts of the device will maintain the relative positions shown in Figure 1 and the tubing may be moved downwardly within the well casing A with the anchoring unit C in an inactive position and the packer elements 22 in their retracted or non-sealing position.

For effecting a release of the latching dogs to permit a relative movement between the tubing and the gripping slips so that the expander cone connected to the tubing may be moved into the slips, a release element in the form of a ring 51 surrounds the section A at a point above the latching dogs 42 of the latch arms 41. This ring has its lower external surface tapered as indicated at 52 and said ring is connected by a plurality of straps or bars 53 with an annular fluid pressure-responsive cup 54. The cup is slidable on the section 11a at a point below the latch arms 41 and has a flexible sealing lip 55 which frictionally engages the bore of the well casing A (Figure 6). The connecting straps or bars 53 which connect the ring 51 with the cup 54 are preferably disposed between the latch arms 41. The release ring 51 and the cup 54 are freely slidable on the tubing section 11a between the latch arms 41 and the enlarged collar 15 at the lower end of the section 11a.

In the operation the device is assembled as illustrated in Figure 1 and is mounted on the tubing string 11 whereby it may be lowered downwardly within the well casing A. At this time the upper shear pin 26 is connecting the mandrel 18 with the perforated connecting section 24 (Figure 4) and the perforated section 24 which has its lower end secured to the expander cone is connected through the lower shear pin 28 with the tubing string. The latch arms 41 are in a position with their dogs 42 engaging the annular recess or groove 48 in the exterior of the tubing section 11a and the inherent resiliency or spring tension of the latch arms maintains this engagement; thus, the gripping slips 30 are latched to the tubing section 11a in a lowered position spaced from the expander cone.

The release ring 51 which has connection through the straps 53 with the piston cup 54 is freely slidable on the section 11a above the latch-

ing dogs and as the device is lowered downwardly through the well casing the fluid pressure from below the cup together with the frictional engagement of the cup member 54 with the wall of the well casing will maintain the cup in a raised position engaging the lower end of the latch arms 41, thereby disposing the release ring 51 in spaced relationship above the latching dogs 42, as is clearly illustrated in Figure 6. It will be evident that so long as the tubing string is moved downwardly the shoulder 49 of the recess 48 in the tubing section 11a will remain engaged with the upper inclined surface 43 of the latching dogs, and thus the gripping slips 30, as well as the expander cone and packing elements, will move downwardly as a unit with all parts being maintained in the relationship shown in Figure 1.

When the position at which the packer is to be set is reached, it is necessary that the latch arms be swung outwardly so that their latching dogs are disengaged from the annular groove or recess 48 and this may be accomplished by applying a pump pressure to the cup member 54, the pressure being applied through the annular space between the tubing and the casing. The pressure applied to the cup member 54 will move said member downwardly on the tubing section 11a and since the member 54 has connection through the straps or bars 53 with the release ring, said ring will also be moved downwardly along the tubing section 11a. At this time, the latch arms will be maintained stationary because said latch arms are connected to the friction shoe assembly and the frictional engagement of the shoes 39 with the wall of the well casing will function to prevent downward movement of the latch arms.

As the cup member 54 moves downwardly to impart downward movement to the release ring 51, the inclined or beveled outer surface 52 of the release ring will move into engagement with the cam surface 47 of the projection 46 and the coaction between these surfaces will result in an outward swinging of the latch arms 41 to the position shown in Figure 10. When this occurs, the latching dogs 42 of the latch arms 41 are swung radially outwardly to clear the recess or groove 48 and thereafter a downward movement may be imparted to the tubing section 11a by the tubing string 11 without the groove engaging the latching dogs. The tubing string and its attached section 11a move downwardly to cause the expander cone 27 to enter the gripping slips 30 which continue to be maintained in a stationary position by the friction shoes 39 and thus the gripping slips 30 are moved into an expanded or gripping position in engagement with the wall of the well casing. After the slips 30 have moved into gripping position as illustrated in Figure 9, further downward movement of the expander cone is prevented and at this point the valve head 12 at the upper end of the section 11a is just slightly above the valve seat 20 at the upper end of the packer assembly. At this time, a circulating or washing operation may be carried out.

When it is desired to set the packing elements 22, sufficient weight is imposed upon the lower shear pin 28 by the tubing string and this disconnects the tubing section 11a from the expander cone whereby continued downward movement of the tubing string may be effected. At this point the valve head 12 engages the valve seat 20 and the weight of the tubing may then be imposed upon the valve seat member 19 and mandrel 18 whereby shearing of the upper pin 26

may be accomplished. As has been noted, the pin 26 connects the mandrel 18 to the expander cone through the perforated section 24, and thus when the pin 26 is sheared the mandrel may telescope the perforated section; since this perforated section is held stationary due to its connection with the expander cone the continued imposition of weight upon the valve seat and mandrel will result in moving the packing elements to an expanded position as illustrated in Figure 3.

The position of the latching slot 48 with respect to the supporting collar 15 at the lower end of the section 11a is in such relationship to the spacing between the cup member 54 and the release collar 51 that when the release collar has engaged the projection 46 to move the latch members outwardly, as has been explained, the cup member is located just above the supporting collar. It might be that upon subsequent downward movement of the tubing string which accomplishes seating of the packer that the release ring will move downwardly below the projection; however, in actual practice, in the fully set position of the packing elements 22 the release ring remains in engagement with the projection 46 and the recess 48 has been moved downwardly in a plane below the latch arms as shown in Figure 10. At this time, the packing cup member 54 is resting and supported upon the collar 15.

From the foregoing it will be seen that the packer may be set without the necessity of imparting any rotation to the tubing string. The application of fluid pressure to the cup member 54 imparts movement to the release ring whereby the latch arms are swung outwardly and disengaged from the latching groove 48. Thereafter, it is only necessary to lower the tubing string to fully set the packer.

After the packer has been set and it is desired to remove the same it is only necessary to lift upwardly on the tubing string which moves the tubing section 11a upwardly. The upward movement of the tubing disengages the valve head 12 from its seat and opens the by-pass passage formed within the mandrel 18. The packing elements 22 and mandrel are supported by the perforated section 24 and the expander cone 27 which is ultimately engaged by the external shoulder 29 on the tubing section 11a whereby these parts are moved upwardly by upward movement of the tubing. The packing cup member 54 will be engaged by the stop or supporting collar 15 at the lower end of the section 11a and will function to support the latch arms and gripping slip assembly as the same are moved out of the hole. It is noted that the recesses 17 which are adjacent the upper end of the supporting collar 15 provide for a by-pass of fluid past the cup 54 when the cup is disposed adjacent said collar. It is therefore evident that upon removal it is only necessary to lift upwardly on the tubing and the entire assembly is thereby released and removed from the well casing. One of the features of the present invention resides in the fact that a premature disengagement of the latch arms from the latching recess 48 will not interfere with the operation. As shown in Figures 4 to 6, with the parts in the position during running in the latching dogs 42 of the arms 41 are engaged with the groove 48. If a pressure should be applied to the packing cup member 54, sufficient to move the release ring downwardly prior to the time that the packer is to be set, this would cause an outward swinging of the latch arms

and would permit a downward movement of the tubing section 11a with respect to said latch arms. However, at this time the tubing is connected through the shear pins 26 and 28 to the expander cone and so long as the pins remain unbroken a resetting of the latch arms can be readily accomplished by merely lifting upwardly on the tubing string. Such upward movement of the tubing would result in the groove 48 again re-engaging the latch dogs 42. The entire assembly is rugged in construction and permits the packer to be set and removed merely by the longitudinal movement or manipulation of the tubing string. It is noted that the gripping slips 30 cannot be expanded beyond a predetermined amount because the stop ring 35 will contact the expander cone to limit the expansion of the slips and this prevents excessive gripping of the casing by the slips.

From the foregoing it will be seen that this invention is one well adapted to attain all of the ends and objects hereinabove set forth together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

Having described the invention, I claim:

1. A well packer device including, a support, a packing element assembly mounted on the support for engagement with a surrounding well wall to seal off between the support and the surrounding wall, an anchoring unit slidably mounted on the support below the packing element and having anchoring means adapted to engage the wall of a well bore to support the packing assembly and permit distortion of the packing element thereof into sealing position, said anchoring means being movable into wall-engaging position upon a relative longitudinal movement of said anchoring means with respect to the support, latching means secured to the anchoring means and engageable with the anchoring means for latching said support against movement with respect to said support whereby the device may be lowered within a well bore, and means slidably mounted on the support and engageable with the latching means for releasing said latching means to thereafter allow relative movement of the anchoring means with respect to the support whereby said anchoring means may be moved into wall-engaging position, said means for releasing the latching means including a pressure-responsive member which spans the space between the support and the wall of the well bore whereby fluid pressure may be applied against said pressure-responsive member to effect sliding movement of the releasing means on the support.

2. A well packer including, a support, a packing element on the support engageable with a surrounding well wall to seal off between the support and the surrounding wall, an anchoring unit below the packing element and slidably mounted on the support and having well wall gripping means adapted to grip the surrounding well wall upon a relative movement of the anchor-

ing unit with respect to the support, latching means attached to the anchoring unit and disposed exteriorly of the support, means on the support engageable by the latching means for latching the anchoring unit against movement with respect to said support during downward movement of the support, a release element slidably mounted on the support and engageable with the latching means for disengaging said latching means from the support, whereby the support may be moved relative to the anchoring unit to actuate the anchoring means thereof, and a pressure responsive member secured to the release element and spanning the space between the support and well pipe, whereby fluid pressure may be applied to said member to impart movement to the release element and thereby actuate the same to disengage said latching means.

3. A well packer including, a support, a packing element on the support engageable with a surrounding well wall to seal off between the support and the surrounding wall, an anchoring unit below the packing element and slidably mounted on the support and having well wall gripping means adapted to grip the surrounding well wall upon a relative movement of the anchoring unit with respect to the support, said support having an external shoulder, a latch arm attached to the anchoring unit and adapted to engage the shoulder upon downward movement of the support relative thereto to thereby latch the anchoring unit against movement with respect to the support, a release ring slidable on the support and normally above the latching shoulder, and a fluid pressure actuatable means connected to said release ring for moving said ring downwardly with respect to the latch arm to engage and swing the latch arm clear of the shoulder upon applying fluid pressure to said means, whereby the support may be moved downwardly relative to the latch arm and anchoring unit to actuate the anchoring means of said unit and anchor the packer within the well pipe.

4. A well packer including, a support, a packing element on the support engageable with a surrounding well wall to seal off between the support and the surrounding wall, an anchoring unit below the packing element and slidably mounted on the support and having well wall gripping means adapted to grip the surrounding well wall upon a relative movement of the anchoring unit with respect to the support, said support having an external shoulder, a latch arm attached to the anchoring unit and adapted to engage the shoulder upon downward movement of the support relative thereto to thereby latch the anchoring unit against movement relative to the support, a release ring slidable on the support and normally above the latching shoulder, said release ring being movable downwardly with respect to the latch arm to engage and swing the latch arm clear of the shoulder, whereby the support may be moved downwardly relative to the latch arm and anchoring unit to actuate the anchoring means of said unit and anchor the packer within the well pipe, and an annular cup member secured to the release ring slidably mounted on the support and spanning the space between the support and the well pipe.

5. A well packer as set forth in claim 4, wherein the annular cup member which is secured to the release ring is provided with an upwardly directed sealing lip, whereby fluid pressure from

above the cup member will urge the same in a downward direction.

6. A well packer as set forth in claim 4, together with a supporting collar on the lower portion of the support engageable by the cup member for preventing downward displacement of the cup member and release ring from the support, said support having by-pass passages adjacent the supporting collar for by-passing fluid around the cup member when said cup member engages the support upon upward movement of the member through the well pipe.

7. In an anchoring unit for well tools, a support, an expander cone mounted on the support, casing gripping slips slidably mounted on the support below the cone, frictional wall-engaging means connected to the slips, latch means secured to the slips and adapted to be detachably fastened to the support for latching the slips to the support in a position spaced from the expander cone, and releasing means slidably mounted on the support and having an element engageable with the latching means for disconnecting said means from the support and for rendering the latching means inactive to permit a relative downward movement of the support with respect to the slips to move the expander cone within the slips and thereby expand the same radially outwardly, said releasing means including an annular sealing cup surrounding the support whereby pressure applied to said cup will impart sliding movement to said releasing means.

8. A well packer including, a support, a tubular mandrel surrounding the support, a resilient packing element mounted on the mandrel for engagement with a surrounding well wall to seal off between the mandrel and the surrounding wall, a slip expanding cone surrounding the support below the mandrel, frangible means initially connecting the expanding cone with the mandrel, a second frangible means connecting the cone with the support, gripping slips slidably mounted on the support below the expanding cone, frictional wall-engaging means connected to the slips, latching means secured to the slips and engageable with the support for latching the slips in a position spaced below the expanding cone, and releasing means slidably on the support and engageable with the latching means to disconnect said latching means from the support, whereby the support and slip expanding cone connected therewith may be moved relative to the slips to expand the same into gripping position, said releasing means including a pressure-responsive sealing element surrounding the support whereby pressure directed against said member will slide the releasing means along said support.
